UNITED STATES PATENT OFFICE

PARL O. ECKELS, OF DALLAS, TEXAS

VALVE GRINDER

Application filed January 16, 1930. Serial No. 421,160.

My invention relates to valve grinders and more particularly to grinders for grinding valves of motor vehicle engines and aeroplane engines without removing the valves from the engines; and the object is to provide simple devices for grinding the valve and its seat simultaneously and to devices which are adjustable to different sizes of valves. One advantage is that the valves 10 are not dismantled or dis-assembled for grinding the valves and thus much time is saved. Another advantage is that the grinding is accomplished by simple manual operation. Other objects and advantages will be 15 fully explained in the following description and the invention will be more particularly pointed out in the claims.

Reference is had to the accompanying drawings which form a part of this application.

Fig. 1 is a section of an engine cylinder, showing the position of the valve and its seat during operation and showing in detail the valve grinding devices, partly in section.

25 Fig. 2 is a plan view of the same.

Fig. 3 is a plan view of the adjustable grinders.

Fig. 4 is a section of the grinders and the arm carrying the same and a section of one 30 of the protecting rollers.

Similar characters of reference are used to indicate the same parts throughout the several views.

The drawings show a section of an engine 35 valve casing and its seat 1 and a valve 2 elevated therefrom to grinding position. The valve 2 is of ordinary type and the head thereof has the usual slot for use in the grinding operation. A screw driver 3 is provided 40 for engaging the valve 2 and an oscillating chuck 4 is mounted on the shank of the screw driver. The chuck 4 is supported in position on the shank 5 by a collar 6 which is made rigid with the shank by a set screw 7. 45 The collar 6 thus forms a bearing for the chuck 4 which is oscillated thereon. A handle or lever 8 rigidly engages the chuck 4 and a knob 9 has a swivel connection with the handle or lever 8. In operation, one 50 hand is placed on the handle 10 of the screw

driver and the other hand of the operator engages the knob 9 for oscillating the chuck.

The chuck 4 is provided with a plurality of socket arms 11 radially disposed. The grinding elements are carried by the socket arms 11. The holders for the grinders are divided into parts hingedly connected together. The socket members 12 are secured in the socket arms 11 by set screws 13 and the grinder carriers 14 are adjustably connected to the carriers 14 by hinged joints so that the grinders can be adjusted to valves and seats having different pitch. Thus, there is a double adjustment for each pair of grinders—radial for valves of different diameters and vertical swinging adjustments for valves having different pitch.

Each carrier 14 is provided with two rollers 15 and 16 which resist the tension of the valve springs and hold the distance between each valve and its seat constant, that is, the rollers hold the seat and the valve at a fixed distance apart. The rollers 15 and 16 also relieve friction by reason that they roll against the valve and its seat both. The 70 grinders or hones are carried by springs 17 and 18 which have their shanks inserted in the carrier 14 and secured therein by pins 19. The hone 20 operates on the valve and the hone 21 operates on the valve seat 22. The 75 springs 17 and 18 have the proper tension for holding the hones against the surfaces to be ground.

In operation, the screw driver 3 is inserted in the usual slot in the valve 2 and the screw 80 driver will hold the valve against vibration while the chuck is being oscillated. The operator places one hand on the knob 10 and holds the chuck 4 in upright position and places the other hand on the knob 9 and oscillates the socket arms and the grinders. There being a plurality of the sockets and grinders operating simultaneously, there is not much tendency to vibrate the valve.

What I claim, is,—

1. A valve grinder comprising a chuck provided with a plurality of socket arms radially disposed, means for rotatably mounting said chuck on a valve head, carrier arms rigidly connected to said socket arms, grind-

er carriers hingedly connected to said carrier arms, rollers carried by said grinder carriers for spacing a valve from its seat, and pairs of grinding elements carried by said 5 grinder carriers, one grinding element of each pair adapted to grind the valve and the other grinding element adapted to grind the valve seat.

2. A valve grinder comprising a chuck provided with a plurality of socket arms radially disposed, means for rotatably mounting said chuck on a valve head, carrier arms rigidly connected to said socket arms, means for fixedly adjusting said carrier arms in said socket arms, grinder carriers hingedly connected to said carrier arms, rollers operatively connected to said grinder carriers for spacing a valve from its seat, pairs of grinding elements yieldingly connected to said 20 grinder carriers, one element of each pair being adapted to grind the valve and the other element adapted to grind the valve seat.

3. A valve grinder comprising a standard to be fixedly connected to a valve, a chuck 25 rotatably mounted on said standard, a collar rigidly connected to said standard for supporting said chuck, said chuck having a plurality of socket arms radially disposed thereon, carrier arms fixedly adjustable in said 30 socket arms, grinder carrying arms hingedly connected to said carrier arms and provided with means for spacing a valve from its seat, means carried by said grinder carrying arms yieldingly for grinding a valve and its seat 35 simultaneously, and a lever for oscillating said chuck.

4. A valve grinder comprising a standard to be fixedly connected to a valve, a chuck rotatably mounted on said standard and provided with a plurality of radially adjustable arms, means adjustably connected to said arms for spacing a valve from its seat and carrying grinders yieldingly connected therewith for grinding the valve and its seat simultaneously, and means for oscillating said 45 chuck.

In testimony whereof, I set my hand, this 2nd day of January, 1930.

PARL O. ECKELS.
